UNITED STATES PATENT OFFICE.

GEORGE I. ROCKWOOD, OF WORCESTER, MASSACHUSETTS.

EXHAUSTER FOR DRY-PIPE SYSTEMS.

Application filed July 29, 1920, Serial No. 399,776. Renewed April 23, 1923.

To all whom it may concern:

Be it known that I, GEORGE I. Rockwood, a citizen of the United States, residing at Worcester, in the county of Worcester and 5 State of Massachusetts, have invented a new and useful Exhauster for Dry-Pipe Systems, of which the following is a specification.

This invention relates to means for facilitating the escape of air from the riser of a 10 dry pipe sprinkler system so as to decrease the time it takes the water to reach the sprinkler head that is opened. The other objects of the invention are chiefly to provide means adapted to be set in operation by 15 a slight decrease in the air pressure in the riser for opening a valve to permit rapid escape of the air therefrom; to provide automatic means for preventing the escape of the water through the air outlet pipe; to provide 20 for preventing the retention of water anywhere in the operating parts in such a way as to interfere with the operation thereof on account of rust or the like; and to provide effective and simple mechanism for carrying 25 out these various functions.

Reference is to be had to the accompanying drawing which is an elevation of a dry pipe valve with a preferred embodiment of this invention applied thereto and shown in 30 central section.

The invention is shown as applied to a dry pipe valve casing 10 connected at the bottom with a water supply pipe 11 and at the top with a riser 12. As is well known this type of valve is used on sprinkler systems in which the riser normally is provided with air under a small pressure as, for example, 50 pounds. The various 35 sprinkler heads are all connected with the riser. When one of them is opened it allows the air to escape which reduces the air pressure in the valve. It is this air pressure that keeps the valve proper 13 closed against the pressure of the water in the pipe 11 which 40 is considerably greater and may be as high as 200 pounds. When the air pressure decreases very materially, say for example down to 15 or 20 pounds, the valve is no longer held to its seat by this pressure. 45 Therefore it opens and lets the water up into the riser from the pipe 11.

Necessarily the opening of but a single head allows the air to escape somewhat slowly and it takes quite a little time for 50 enough air to escape to reduce the pressure

sufficiently to open the dry pipe valve. This has always been a defect of this type of sprinkler system. Another objection lies in the fact that the air coming from the sprinkler head is forced out under such a 60 high pressure that its influence is felt at a considerable distance from it. There is always danger that papers, sawdust, and other light articles, likely to be the first to catch fire, may be in the vicinity of the 65 sprinkler head that is opened. They are likely, therefore, to be blown around and thus spread the fire.

As stated above, this invention has for its main object the provision of means for exhausting the air from the riser, at a point remote from the fire and more rapidly than can be done through a single sprinkler head or even any number of them that are likely 70 to be opened at the same time when the fire starts. It also involves, in addition to the objects above mentioned, the arrangement of the parts for this purpose in such a way as to insure the system against wastage of 75 water while in operation, and to prevent the exhaustion of the air from the riser by operating prematurely when the sprinkler heads are all closed.

I have shown the riser as provided, preferably at the top of the system, with an 80 exhaust pipe 15 connected with a valve casting 16. This has a valve seat 17 through which the air from the riser can be exhausted. I provide a valve 18 for this seat with a spring 19 surrounding its stem and 85 pressing on a disc 20 for normally holding this valve open. Thus the air from the riser communicates with the parts of the valve casting 16 located beyond. This disc 20 is located on a diaphragm 21 in a casing 90 22. The air space 23 under this diaphragm is connected by a pipe 24, which may have a drip valve 25, with the intermediate chamber 26 of an ordinary dry pipe valve. This chamber, as is well known, is sealed by the 95 valve 13, when that is closed, so that the pipe 24 is cut off from any pressure of the water system. When the main valve 13 opens the water under pressure from the water system has free access to the lower end 100 of the pipe 24 and will close the valve 18 for a purpose to be described hereinafter. I also provide means whereby the water pressure will not be transmitted too quickly 105 to the diaphragm. This is shown in the 110

form of a restricted inlet 27 to the pipe 24. The design of the valve 18 and its mountings also assist this object, inasmuch as the trapped air under the diaphragm must be compressed to a sufficient pressure to overcome the reaction of the spring 19 and the system air pressure on the valve 18 holding its lower face against the seat 60.

The valve casing 16 is also provided with 10 another valve seat 30 normally closed by a valve 31 having a spring 32 behind it for that purpose. Under this valve seat and in position to receive the air or water from the pipe 15 is a chamber 33 which may conveniently 15 constitute a part of the valve casing 16. Its bottom is closed by a member 34 screwed into it and having a passage through it which constitutes a guide for a striker 35. The member 34 has an enclosed 20 portion extending downwardly through which the striker passes and at the bottom is provided with a cap 36 having a port 37 through which the end of the striker protrudes. A spring 38 rests on this cap and 25 presses upon a flange 39 on the striker. The chamber 33 has an outlet 40.

The bottom end of the striker is pivotally connected with a lever 42 the outer end of which rests on the top of an arm 43 which 30 constitutes part of a lever 44. The end of this lever 44 is operated by a pair of pneumatic diaphragms 47 and 48. It is shown as resting in a groove 45 in a block 46 against the opposite parallel sides of which 35 the two diaphragms are tightly bolted. These diaphragms constitute the bottom and top of an annular casing 49 to the flanges of which are fixed a hollow cap 50 and an air chamber 51, one above and the other 40 below. These six parts, 46, 47, 48, 49, 50, and 51, are bolted together and are hermetically sealed, except as to the interior of 49. They are shown as being fixedly connected with the member 34 by an arm 52. The air chamber 51 is air tight, but is provided with a 45 drip valve 53 for an obvious purpose. The air space in the cap 50 above the diaphragm 48 communicates with the interior of the valve casing 16 through a pipe 54.

50 The two diaphragms 47 and 48 are held constantly at the same distance apart by the block 46, the weight of which tends to depress them, and the pressure of the air in the riser is communicated normally to the 55 chamber in the cap 50 to hold the block 46 down. However, this double diaphragm arrangement has a balanced air pressure on it under normal conditions and then is held down by gravity. A balanced air pressure 60 on the two diaphragms 47 and 48 is secured by providing a small passage 56 through the block 46 so restricted that although the chambers 50 and 51 thus communicate freely through this passage, it prevents instantaneous 65 equalizing of the air pressure in each

when, for any reason, they become materially unbalanced.

The operation of the device will now be explained. Under operating conditions the parts are in the position illustrated and the dry pipe valve proper 13 is closed. If fire 70 opens a sprinkler head the pressure in the riser is soon slightly reduced. This reduction is communicated immediately to the chamber 50, but it takes a longer time for 75 the pressure in the chamber 51 to decrease to the same extent, owing to the small size of the restricted air passage 56, and as the pressure below diaphragm 47 now over balances that above 48 the block will rise. This 80 takes up with it the inner end of the lever 44 and swings outwardly the arm 43 that held the striker down through the lever 42. The spring 38 which is designed to exert 85 a much more powerful force than the combined resistance of the spring 32 added to the system air pressure on the back of the valve 31, is now at liberty to force the striker up. This action immediately takes place and opens the valve 31, thus giving a 90 free exit to the air in the riser through the pipes 15 and 40. The result of this is both to exhaust the contained air in the system to a safe place and to open the main dry pipe valve much sooner than it would have 95 opened without this mechanism.

When by the foregoing operation the main valve has opened, water flows into the riser and toward the sprinkler heads and also into the pipe 15. But before it arrives at 100 pipe 15 the water has passed through the pipe 24 and raised the air pressure under diaphragm 20, thereby closing the valve 18 and sealing the system. The restricted inlet prevents this action taking place before 105 air contained in the riser has had an opportunity to escape through pipe 15.

It is desirable to exhaust all the air in the system possible before closing this valve. Therefore to get the full benefits of the invention in respect of exhausting as much of the air in the system as possible before water 110 actually wastes through pipe 15 it is necessary to select such a volume in pipe 24 and casing 23, together with such a weight of valve 18, unbalanced air pressure on valve, and stiffness of spring 19, as will just permit the elapse of the time required to accumulate sufficient pressure under diaphragm 21 to close valve 18 before water 115 ascending the riser reaches pipe 15.

After the valve 18 has been shut the air pressure in all chambers of the device except 23 falls to that of the atmosphere. Then gravity will restore the block 46 to the position shown provided the lever 42 is raised, by hand or otherwise, to permit of 120 this motion. The striker 35 is thus locked in the position shown and the valve 31 closes. When the fire is under control the main 125

valve 11 is closed and the water in the system drawn off. The dry pipe valve is also closed and then put under pressure in the usual way. The air or water in pipe 24 is allowed to escape by opening the drip valve 25 which is then closed. In this way all the parts are restored to the position shown in the drawing.

It is to be observed that in addition to the effective operation above described, several contingencies are provided for by the mechanism shown. For example, there is no stuffing box around the striker 35, but only a loose fitting guide. Therefore, any water that escapes into the chamber 33 is free to find its exit through port 37. The entrance of the air under pressure into the chamber 50 will not disturb the relationship of the parts connected therewith because they are already restored to normal position first. The stem of the valve 18 is guided loosely through the opening.

Although I have illustrated and described only a single form of the invention and shown it as applied only to a specific type of dry valve, I am aware of the fact that numerous modifications can be made in the construction and relative arrangements of the mechanism, and that it can be applied to other types of dry pipe valves without departing from the scope of the invention as expressed in the claims. Therefore I do not wish to be limited to the details of construction or specific form of dry pipe valve herein shown and described, but what I claim is:

1. In a dry pipe valve system, the combination with the dry pipe valve, a main for supplying the water thereto, and a riser, of an air chamber, a pneumatic device closing one end of the air chamber, the other side of said pneumatic device communicating freely with said riser to place a pressure equal to the pressure in the riser on one side thereof, means for allowing leakage constantly from one side of the pneumatic device to the other to balance it normally, and means, operated by the action thereof, for releasing to the atmosphere the air under higher pressure in the riser when its pressure has been slightly reduced by the opening of one or more sprinkler heads.

2. In a dry pipe valve system, the combination with the dry pipe valve, a water main for supplying water under pressure thereto, and a riser normally containing air under a lower pressure, of an air chamber, a double diaphragm closing one end of the air chamber, the other side of said diaphragm communicating freely with said riser to place a pressure equal to the pressure in the riser on one side of the diaphragm, means for allowing leakage constantly from one side of the diaphragm to the other to balance the diaphragm normally, and means, operated by

the action of said diaphragm, for releasing the pressure in the riser when that pressure is slightly reduced.

3. In a dry pipe valve system, the combination with the dry pipe valve, a main for supplying water thereto, and a riser containing air, of a closed air chamber, a second air chamber connected with the riser and normally having the same pressure, means for permitting restricted leakage between said two air chambers, and means whereby a slight reduction of pressure in the chamber connected with the riser will open the riser to the atmosphere and allow the air in the riser to escape rapidly therefrom.

4. The combination with a dry pipe valve system, having a riser normally containing air under pressure, of a closed air chamber, a second air chamber connected with the riser and therefore having the same pressure, means for permitting leakage between said two chambers, a valve normally preventing the escape of air from said riser, a device for positively opening said valve, means for operating said device, and means normally held in position to prevent the action of said means when the pressures in said two chambers are equal and arranged to release said means when the pressure in the said closed air chamber is greater than that in the chamber connected with the riser.

5. The combination with the air riser of a dry pipe valve system, of an air chamber, a diaphragm closing one end of the air chamber, the other side of said diaphragm communicating freely with said riser to place a pressure equal to the pressure in the riser on one side of the diaphragm, means for allowing leakage constantly from one side of the diaphragm to the other to balance the diaphragm normally, a lever, a locking device connected with the diaphragm and operated thereby to hold the lever locked, a striker connected with the lever, an air release valve and means adapted to be released by the unlocking of said striker for forcing the striker into a position to open the valve.

6. The combination with the air riser of a dry pipe valve system, of an air chamber, a pneumatic closing one end of the air chamber, the other side of said pneumatic communicating freely with said riser to place a pressure equal to the pressure in the riser on one side of the pneumatic, means for allowing leakage constantly from one side of the pneumatic to the other to balance it normally, a lever, a locking device connected with the pneumatic and operated thereby to hold the lever locked normally, an air release valve a striker connected with the lever, and means adapted to be released by the unlocking of said striker for moving the striker into a position to open the valve, a chamber into which the air from the riser is

discharged, said chamber having a loose guide for the striker through which any water collected in said chamber is free to escape.

5 7. In a dry pipe valve system, the combination with the dry pipe valve and the riser, of means communicating therewith for opening the riser to the atmosphere upon a slight reduction of pressure therein, a second valve held normally open, and means connected with the dry pipe valve for closing the open valve when the dry pipe valve opens.

8. In a dry pipe valve system, the combination with the dry pipe valve, a water main for supplying water under pressure thereto, and a riser normally containing air under a lower pressure, of means communicating with the riser for opening the riser 15 to the atmosphere upon a slight reduction of pressure in the riser, a second valve adapted to be held normally open by the combined action of gravity and pressure in said riser, and means connected with the dry pipe valve for closing the open valve when the dry pipe valve opens, said means being restricted to prevent premature closing of said second valve.

9. In a dry pipe valve system, the combination with the dry pipe valve having an intermediate chamber, and a riser normally containing air under pressure, of a pipe connected with the riser, a valve normally closing said pipe, means also connected with the riser for positively opening said valve and allowing the escape of air from said pipe when the pressure in the riser is reduced, a pipe connected with the intermediate chamber in the dry pipe valve and normally protected from air or water under pressure by said valve when closed but adapted to be open to communication with water under pressure when the dry pipe valve opens. A pneumatic device connected with the last

named pipe and arranged to be raised when the pressure is introduced into the same, a valve connected with said pneumatic and adapted to be closed thereby to close the first named pipe, and means for normally holding the last named valve open. 45

10. In a dry pipe valve system, the combination with the dry pipe valve, a water main for supplying water under pressure thereto, and a riser normally containing air under a lower pressure, of a pipe connected with the riser, a valve normally closing said pipe, means also connected with the riser for positively opening said valve and allowing the escape of air from said pipe when the pressure in the riser is reduced, a pipe connected with the intermediate chamber in the dry pipe valve, and normally disconnected from said water main by said valve when closed, but adapted to be opened thereto when the dry pipe valve opens to admit the 65 water from the system into said pipe, a diaphragm connected with said pipe to be raised when pressure is applied from the water main, a valve connected with said diaphragm adapted to be closed thereby, and a 70 spring for normally holding the last named valve open. 50

11. In a dry pipe system, the combination with an air chamber, an inlet connection to said chamber from said pipe system, said chamber also having an exhaust opening, a valve for closing said exhaust opening, and means to open and close said valve, of a second air chamber, said valve being opened by means of excess air pressure in said second 75 chamber and permitting the escape of the air from the system and being adapted to be closed upon the occurrence of excess air pressure in the first named chamber. 80

In testimony whereof I have hereunto affixed my signature. 85

GEORGE I. ROCKWOOD.
